US0D1023277S

(12) **United States Design Patent** (10) Patent No.: **US D1,023,277 S**
(45) Date of Patent: ** Apr. 16, 2024

(54) **STERILIZING ATOMIZER HAND OPERATED**

(71) Applicant: **Guy Whitmore**, Leicestershire (GB)

(72) Inventor: **Guy Whitmore**, Leicestershire (GB)

(**) Term: **15 Years**

(21) Appl. No.: **35/517,222**

(22) Filed: **Feb. 6, 2023**

(80) **Hague Agreement Data**

Int. Filing Date: **Feb. 6, 2023**

Int. Reg. No.: **DM/228779**

Int. Reg. Date: **Feb. 6, 2023**

Int. Reg. Pub. Date: **May 19, 2023**

Primary Examiner — Keith J Wilson

(57) **CLAIM**

The ornamental design for a sterilizing atomizer (hand operated), as shown and described.

DESCRIPTION

The patent or application file contains at least one drawing executed in color. Copies of this patent or patent application publication with color drawing(s) will be provided by the Office upon request and payment of the necessary fee.

1. Sterilizing atomizer (hand operated)

This article is used for production of Hypochlorous Acid (HOCL) in situ through electrolysis in the middle tank to sanitize toilets through a specifically designed atomizer handle; **1.1 Internal view**; **1.2 Right side angle view**; **1.3 Left view with HOCL feed**; **1.4 Right view with water inlet**; **1.5 Front view closed**; **1.6 Back view**; **1.7 Top view**; **1.8 Bottom view**; **1.9 Detailed view of electrode**; **1.10 Detailed view of handle**.
